BOX STAY

Edward H. Angier, Framingham, Mass., assignor
to Edward H. Angier, Framingham, Mass., as
trustee

Application August 8, 1935, Serial No. 35,299

1 Claim. (Cl. 229—49)

This invention relates to reinforced strips for use as box stays or the like, and the object is to provide an improved stay strip for adhesive connection to a box of fiber-board or similar material to join or reinforce the joint between opposed edges or other parts of the box. The construction and advantages arising therefrom will be well understood by those skilled in the art by reference to the following description of an illustrative embodiment thereof shown by way of example in the accompanying drawing, wherein:—

Fig. 1 is a perspective view of a box having a form of stay illustrative of my invention applied thereto; and

Fig. 2 is a fragmentary plan view of a portion of the stay strip with parts broken away.

In Fig. 1 of the drawing I have shown the box 5 having an edge thereof where the ends of the blank join secured by a stay 7 embodying my invention and have also shown the stay 7 securing together the cover flaps 9 and extending down the sides of the box in the customary manner. The stay strip 7, as best seen in Fig. 2, 10 is in the form of a narrow band which may be provided with a gum coating 11 which may be moistened to secure the stay in position on the box, the band herein consisting of two strips 13 and 15 of kraft or like strong paper, which 15 bands are united by intervening waterproof adhesive, such as black asphalt 17. Incorporated with the base strip paper stock, herein by being embedded in the asphalt 17, is a strand-like reinforcement, herein shown as consisting of a single 20 continuous yarn 19 of cotton, jute or the like. This reinforcement is here shown as extending across the central portion of the band where the joint of the box would occur, across substantially the entire width thereof, yet received as 25 a whole within the longitudinal ends of the band, and may be zigzagged back and forth as shown to provide diagonally disposed parts relatively closely adjacent one to another and which make substantially great angles with the length of the 30 strip. That is, preferably, while generally diagonal, the separate sections of the zigzag curve are more nearly transverse than longitudinal. The reinforcement 19 is substantially single, that 35 is to say, at least in the central portion of the band there are no interweaving or crossings forming a reticulation, but on the contrary the reinforcement is the single thickness of strand, although it will be understood that a plurality of strands might be applied side by side and 40 handled substantially as one.

Boxes at the present time are commonly stayed, sealed or reinforced with cloth tape or with gummed kraft tape. I am also aware that it has been proposed to reinforce paper in various ways by associating textile strands therewith. Thus, 5 for example, in the patent to Angier 1,195,430, dated Aug. 22, 1916, there is disclosed a gummed stay tape for use on a box, reinforced by separate textile strands extending across the same at right-angles to its length. Such strands serve to reinforce the corner of the box. The diagonally disposed parts of the strand 19 herein illustrated 10 similarly reinforce the corner of the box particularly because of their more nearly transverse disposition but have further advantages. 15 The principal strain which might disrupt the strand is a bursting strain at the joint between the box parts which the stay bridges tending to split the tape along this joint. Since to provide a tape of indefinite length the grain of the paper 20 must be longitudinal thereof, the stay is relatively frangible along such a line. With the tape reinforced with strands at right-angles, if the paper split the split would continue until it encountered a strand. If the strain were sufficient to snap 25 this strand or to tear it away from the soft, lentous adhesive, such as asphalt, which secured it, the tear would continue or in certain instances the split of the paper might continue along the 30 grain without breaking the strand until a substantial length of the paper closing the joint was ruptured although the edges of the box parts might still be secured together by unbroken strands. In the case of a stay such as herein disclosed, if the paper starts to split, when it 35 encounters a strand the tendency is to divert the tear along the strands into the areas of paper secured to the box parts at either side of the joint and there is less tendency for the tear 40 to be propagated along the joint in the manner described, and even if the tear runs out to the edge of the tape along the line defined by the reinforcing strand, the strength of the joint is relatively slightly impaired. Furthermore, if the 45 reinforcing strand is secured by a lentous adhesive, such as asphalt, if a tear strikes one of the transverse parts it may draw a little through the asphalt on the bights or loops at the side tending to absorb the shock and in fact the 50 strand without bursting may be pushed down toward the next lower strand in the direction of strain, tending to present two lengths of strand substantially together as a resistance to rupture and further propagation of the tear. 55

The stay strip as described is readily and cheaply constructed and is of substantially uniform thickness about its area. It is thus easy to handle, whether manually or mechanically, and easy to gum or moisten. As the edge portions extend slightly beyond the reinforcement, they are sealed and the strand completely protected.

I am aware that the invention may be embodied in other specific forms without departing from the spirit or essential attributes thereof, and I therefore desire the present embodiment to be considered in all respects as illustrative and not restrictive; reference being had to the appended claim rather than to the fore-

going description to indicate the scope of the invention.

I claim:—

A stay strip for adhesive application along box corners and for like purposes comprising two 5 ribbon-like strips of paper united by adhesive and having between them and received in said adhesive between their longitudinal edges a substantially single reinforcing strand disposed along the length of the tape in a zigzag of rapid 10 periodicity and providing an unreticulated reinforcement having parts disposed in diagonal positions approximating the transverse.

EDWARD H. ANGIER.
